UNITED STATES PATENT OFFICE.

HAROLD V. RUDOLPH, OF CHARLOTTESVILLE, VIRGINIA, ASSIGNOR TO AMERICAN AUTOMATIC TRAIN CONTROL CORPORATION, OF BALTIMORE, MARYLAND, A CORPORATION OF MARYLAND.

SPEED-CONTROL MECHANISM FOR VEHICLES.

Application filed February 3, 1920. Serial No. 355,993.

To all whom it may concern:

Be it known that HAROLD V. RUDOLPH, a citizen of the United States, residing at Charlottesville, in the county of Albemarle 5 and State of Virginia, has invented certain new and useful Improvements in Speed- Control Mechanism for Vehicles, of which the following is a specification.

This invention relates to an improved 10 speed-control mechanism for automatic train-control systems and is especially designed for use in that class of train control systems wherein a contact shoe is carried on the vehicle and so arranged as to be moved 15 by contacting with ramp rails along the trackway whereby to operate a shoe-switch on the vehicle and open or close circuits to break down or maintain the vehicle mechanism according to the conditions of the track 20 ahead.

In said systems it is usually planned, when the track ahead is clear, to pick up a current from the ramp-rails and substitute it for the normal vehicle current while the shoe- 25 switch is open, and in case the track ahead is occupied, to cut-off the current from the ramp-rail which guards the occupied section of track, so that no current can be picked up to be substituted for the broken vehicle circuit, and thus deenergize magnets in the 30 vehicle that will cause an automatic stop of the vehicle.

It has now been found desirable in rail-road operations to permit a vehicle to enter 35 an occupied block or section provided the speed of the vehicle is reduced to a point of safety, and the object of the present invention is to provide improved mechanism on the vehicle whereby the vehicle mechanism may be maintained in an energized 40 condition when a deenergized ramp-rail or current source on the trackway is cut off, only however in case such vehicle is traveling at a sufficiently low speed to be deemed 45 safe.

Another object of the present invention is to provide an improved arrangement of circuits and circuit closers all on the vehicle whereby to permit a vehicle traveling at a 50 safe speed to enter an occupied block or section of track.

With the above objects in view the inven-

tion is illustrated in the accompanying drawing wherein the single view shows diagrammatically the devices and circuits employed 55 on the vehicle and embodying the invention.

Referring to the drawing the numeral 1, designates a track-rail; 2 a comparatively long and gradually-inclined ramp-rail which normally, when the track ahead is clear is 60 connected to one side of a ramp-rail current- supply 3, through a track-relay 4. The other side of the current-supply 3, has a connection with the track-rail 1, while the track-relay 4, is controlled through wires 5 and 6 65 by a circuit that is normally closed when the track ahead is clear and open when the track ahead is occupied or in a dangerous condition.

All of these features are common in train- 70 control devices now in use and are not claimed in themselves by me.

On the vehicle I provide a plurality of circuit breakers or switches 7 and 8 and a plurality of switch contacts 9 and 10 for one 75 switch and 11 and 12 for the other switch.

The two switches are designed to be moved simultaneously and are so arranged that when one is moving in a direction to open one circuit the other is moving in a direction to effect a closure of another circuit. 80

It is not essential just what means be employed to effect a movement of the two switches but in the present instance I show a stem 13, connecting the two switches and 85 carrying a contact shoe 14, at its lower end which shoe is so located on the vehicle as to engage in succession the ramp-rails 2, which are provided at intervals along the track-way and are so inclined as to impart 90 a vertical movement to the shoe, stem and switches as each ramp-rail is passed.

In the present instance the switch 7, is designed with an upper contact surface and a lower insulating surface 15, which latter 95 will not conduct electrical current.

On the vehicle I provide a control relay which in practice is designed as a combined electro-pneumatic valve 16, of such construction as to effect a venting of the train-line 100 of an air-brake system when the magnet is deenergized and thereby apply the air-brakes. This control relay is of a well-known construction and a detailed illustra-

tion of the same is deemed unnecessary in this case.

The control relay has an armature 18, which latter is held up, when the relay is energized, so as to engage a contact 19, and the armature is connected by a wire 20, to one side of a vehicle current supply 21. Connections 22, 23 and 24, are provided from the other side of the vehicle current supply 21 to the control magnet 16, and connections 25 and 26, extend from said control magnet 16, to the shoe-switch contact 9.

It will also be noted that from shoe-switch 10, I provide connections 27 and 28 to the contact 19, with which armature 18, contacts.

From the above explanation it will be seen that normally the vehicle current supply 21, keeps the control-magnet 16, energized when switch 7 is in engagement with contacts 9 and 10 and that the circuit thus maintained through the control-magnet is a stick-circuit because it includes the armature 18, of the magnet which it energizes.

It is to be particularly noted that the switch-contacts 9 and 10 which the switch 7, engage are so disposed that when the switch moves up the contact 10, after a certain movement of the shoe has been made, will be engaged by the insulation 15, whereas the contact 9, will always engage the contact surface 7, and that when the contact 10, is on the insulation 15, the normal circuit across the switch 7, between said two contacts 9 and 10, will be interrupted.

Just what occurs upon the interruption of the normal circuit across the switch 7, depends on whether the track ahead is clear, or if occupied, upon the speed of travel of the vehicle, and these conditions will presently be explained.

I further provide on the vehicle what may be termed a speed-control relay, or for brevity a speed-relay 29, which latter has a stem 30, carrying an armature 31, the lower end of which stem is connected to a retarding device 32, such for example as a dash-pot so that when the speed-relay 29 is energized, the armature 31, can pick up only as fast as the retarding device 32, will permit.

The speed-relay has one connection with one side of the vehicle current-supply 21, through the wires 22, 23, and 33 and the speed-relay which terminates at the switch-contact 11.

This latter connection includes wires 34 and 35, and in the present instance, I show a spring switch 36, interposed in this latter connection between wires 34 and 35, but this is not essential to the operation of the apparatus, and is only provided as a check on the engineer, as will presently be more fully explained.

From the contact 12, of shoe-switch 8, I provide connections 37 and 38 which unite

with wire 28, so as to provide a connection from the said contact 12, to the battery 21.

It is therefore to be noted that when control-magnet 16, is energized and shoe-switch 8, is closed with contacts 11 and 12 and the spring-switch 36, if used, is also closed, that a circuit will be complete through the speed-relay 29 from battery 21, by wires 22, 23, 33 to said relay, then by wire 34, spring-switch 36, wire 35 to contact 11; then across 75 shoe-switch 8, to contact 12; then by wires 37, 38 and 28, to armature-contact 19; through the armature 18, (up) and by wire 20, back to the battery.

The circuit just described will, upon its 80 completion, energize speed-relay 29 and thereby exert an upward pull on the stem 30, which latter is retarded in its up movement by the dash-pot 32, but when the up-stroke is completed the armature 31, of this 85 speed-relay will close a substitute circuit through the control-magnet 16, and hold the latter energized provided the same (magnet 16) has not already become deenergized by the interruption of the normal circuit by 90 the movement of the switch 7, from the contact 10.

This latter break in the normal circuit through control-magnet 16, will not occur, in my present device, until after the substitute circuit has been closed, provided, and only provided the speed of the vehicle is low and safe because if the speed of the vehicle is too great the switch 7 will move up and open the circuit between contacts 7 and 9 before the speed-relay 29 will close the substitute circuit at the armature 31.

This substitute circuit, through the speed-relay armature 31, is as follows: from vehicle current-supply 21, by wire 20, armature 18, contact-point 19, wires 28, 38 and 39, to a spring-switch 40, if the latter is used which must be held closed by hand; across the switch to wire 41; then through armature 31, to wires 42 and 25, to control-magnet 16; 105 then by wires 24, 23 and 22, back to the vehicle current-supply 21. It is to be noted that this speed-control substitute circuit is also a stick-circuit in that it energizes control-magnet 16, through the armature of the 110 latter.

This substitute circuit also includes the spring switch 40, between wires 39 and 41, but this spring-switch is also not essential to the operation but is included in the circuit so that in case the dash-pot 32 should stick and hold armature 31 closed, the circuit would be interrupted immediately upon release of the switch 40, by the engineer. Obviously if this substitute circuit should accidentally remain closed, then control-magnet 16, would always be kept energized even when the vehicle enters an occupied block at high speed, and this is just what the invention seeks to prevent.

The operation of the invention is as follows:

Presuming the track ahead of the vehicle to be clear and the vehicle approaching, but not yet in engagement with the ramp-rail 2, on the trackway, the normal vehicle circuit from the vehicle current-supply 21, through the control-magnet 16, will be the stick-circuit shown in the drawing which includes the armature 18, of the said control-magnet; the wires 26 and 27; the switch 7 and its contacts 9 and 10 and the wires 22, 23, 24 and 25. At this time all other circuits shown in the drawing will be open.

When the track ahead is clear, track-relay 4 will be energized so that its armature will be held up and thus provide a connection from one side of the ramp-rail current-supply 3 to the ramp rail 2. When the shoe 14 therefore rides up onto the comparatively long and gradually-inclined ramp-rail the stem 13 and both switches 7 and 8 connected thereto will move up, and during this up-movement, the contact 10 will be engaged by the insulated portion 15 of the switch and thereby effect an interruption of the circuit across the switch from contact 10 to contact 9, but said contact 9 will remain in engagement with the switch 7, for a purpose that will now be explained.

The engagement of shoe 14, with the ramp 2, will form an electrical connection between the two and current from source 3 will be picked up by the shoe and conducted by the stem 13, through switch 7, to contact 9 then by wires 26, and 25 to and through control-magnet 16, then by wires 24 and 23 to a wire 43, that extends to the axle 44, and wheel 45; then through track-rail current supply 3.

Thus it will be seen that the control-magnet 16, will be kept energized when the track ahead is clear, (and a ramp-rail is engaged by the shoe) by the current picked up from current supply 3.

This operation is not new in my present invention but is one that is in practice and in conjunction with which my invention is used.

Let it now be presumed that the track ahead is occupied but that a vehicle travelling at a low and safe speed enters the block or section already occupied.

In this example, of course the ramp-rail 2 would be dead because current from supply 3 would be cut-off by the deenergized track-relay 4.

When the slow-moving vehicle reaches the comparatively long and gradually-inclined ramp-rail 2, the shoe 14, will ride up onto the same, slowly as compared with the movement when the vehicle is traveling at high speed. The upward movement of shoe 14; stem 13, and switches 7 and 8, will be comparatively slow but switch 8, will close

between contacts 11 and 12 immediately after beginning its upward movement and before the switch 7, opens the normal circuit between contacts 9 and 10, so that before the normal circuit between switch 7 and its contacts 9 and 10 and the control-magnet 16, is broken, the substitute circuit formed by the switch 8 and contacts 11 and 12, through the speed-relay 29, will be established whereby to energize the speed relay and start the stem 30 and armature 31 moving upwardly. This upward movement is so timed by the dash-pot 32, that the armature 31 will also close with the connections 41 and 42 before the switch 7 has passed from the lower contact 10, consequently the substitute circuit from the vehicle current-supply 21, through the armature 31 and the control-magnet 16, will be established before the normal circuit from the same current-supply 21, through the contacts 10 and 9 and switch 7, is broken. This operation depends upon the period of time that ensues between the closing of switch 8 with contacts 11 and 12, and the movement of the switch 7 from contact 10, and this time period in turn is varied according to the speed of the vehicle and the speed at which the shoe-contact 14, is moved up as it passes over the long and gradually inclined ramp rail 2.

It seems to be obvious that when the vehicle moves slowly the movement of the shoe and its switches will be correspondingly slow so that the speed-magnet will have time to pick up its armature 31, before the switch 7, interrupts the normal vehicle circuit.

When armature 31 picks up, then the substitute circuit will be formed and this circuit will also be a stick-circuit because it includes the control magnet 16, and the armature 18, which that magnet controls.

In the present illustration I have interposed the two spring-switches 36 and 40, in the speed-magnet circuit and in the substitute control-magnet circuit because I prefer to require the attention of the engineer when it is desired to enter a block already occupied,—he having been previously warned, by either wayside or cab signals, that he is about to pass a dead ramp-rail. By this means the engineer is required to close the switches 36 and 40 and hold them closed while the shoe 14, is passing over the ramp-rail 2 and unless he does so the movement of the shoe, either fast or slow will fail to close either the speed-relay or the control-magnet circuits and an automatic stop will result.

From the above explanations it is to be understood that the present invention combines a control device, a retarded speed-control element, a current-supply and two shoe-actuated switches, all on the vehicle and connected by electric connections, with means to cause a fast or slow movement of

the shoe-actuated switches whereby a slow movement of the switches will cause a substitute circuit to be formed by the speed-control element from the vehicle current-supply through the control device, when the track ahead is occupied whereas, under the same track conditions, a fast movement of the switches will cause the control device to automatically operate to stop the vehicle and 10 a fast movement of the switches with the track ahead clear will cause another circuit to be formed through the control device to prevent operation of the latter.

Another feature and advantage of my 15 present invention lies in the fact that if a vehicle is stopped with its contact-shoe 14, resting upon a dead ramp-rail 2, as frequently happens in practice, no difficulty is experienced in resetting the mechanism and 20 restoring the normal circuits so the vehicle can proceed.

This resetting operation, under the present invention is extremely simple and as follows:

It should be remembered that when the 25 contact shoe 14 is on a dead ramp-rail, the switch 7 will be elevated and the contact 10 will then be in engagement with the insulation 15, and of no utility as a current conductor.

30 This position of contact 10 opens the normal vehicle circuit for control magnet 16, and deenergizes the latter and causes an operation of the air-brakes or control devices. It should be remembered that this normal 35 vehicle circuit through the control magnet is a stick circuit, in that it includes the armature 18, of said magnet, and cannot be restored until the armature 18 is picked up.

The resetting of relay 16 is effected after 40 the vehicle has stopped by means of a substitute circuit on the vehicle, and the substitute circuit is completed by manual operations of the engineer who lifts armature 18 and depresses cross spring switches 36 and 40; whereupon current from vehicle current-supply 21, will flow by wire 20, through the manually held-up armature 18, contact 19, wires 28, 38, 8, to contact 11; then by wire 35, to and through the spring switch 36, which is manually held closed; then by 45 wire 34 through speed relay 29, energizing

the latter and drawing its armature 31 gradually up; then by wires 33, 24, 23 and 22 back to the current supply 21.

When speed relay 29 is thus energized and 55 its armature 31 lifted, spring switches 36 and 40 and the armature 18 will be held closed by hand. As soon as armature 31, closes across wires 41, 42, the substitute vehicle circuit through control magnet 16, will 60 be completed as follows: From vehicle current supply 21, by wire 20, armature 18, contact 19, wires 28, 38 and 39 to and through spring switch 40; then by wire 41, armature 31, wires 42 and 25 to and through control magnet 16; then by wires 24, 23 and 22 back to vehicle current supply, thereby 65 energizing control-magnet 16, and holding armature 18 up. The engineer will then 70 hold switches 36, 40 closed and move his vehicle forward until the shoe leaves the ramp rail and when the shoe moves down the switches 7, will again close the normal vehicle circuit between contacts 9 and 10 and 75 control magnet 16 will be held energized.

The engineer may then release the armature of the control relay 16, which latter will remain in the normally energized condition.

Having described my invention, I claim,— 80

In a train control apparatus the combination with a vehicle having a controlling device, of a current supply on the vehicle; plural pairs of switch contacts and shoe actuating means therefor also on the vehicle; means to effect an operation of the shoe means as the vehicle travels; a normally closed circuit on the vehicle between the vehicle current-supply one pair of switch-contacts and the controlling means; a magnetic 90 circuit-closer and means for retarding its action also on the vehicle; normally-open connections also on the vehicle and including the vehicle current-supply another pair of said switch-contacts and the retarded 95 magnetic circuit closer; and means for forming a substitute stick-circuit on the vehicle from the vehicle current-supply through the controlling-device when the said normally-open connections are closed.

In testimony whereof I affix my signature.

HAROLD V. RUDOLPH.
